TELL-TALE FLEXIBLE STAYBOLT

Application filed January 20, 1931. Serial No. 509,997.

This invention relates to staybolts for boilers, and has special reference to staybolts of flexible type.

Under the Interstate Commerce rules it is required that all flexible staybolts having caps over the outer ends shall have the caps removed at least once every two (2) years and the bolts and sleeves examined for breakage, except in cases where the bolt is provided with a tell-tale hole not less than three-sixteenths ($\frac{3}{16}$) of an inch nor more than seven thirty-seconds ($\frac{7}{32}$) of an inch in diameter, extending the entire length of the bolt and into the head not less than one-third (1/3) of its diameter, and these holes are protected from being closed by copper plating or other approved method, and are opened and tested, each time (at least yearly) the hydrostatic test is applied, with an electrical or other instrument approved by the Bureau of Locomotive Inspection, that will positively indicate when the tell-tale holes are open their entire length, in which cases the caps will not be required to be removed. When this electrical indicating test is completed the hydrostatic test must be applied and all staybolts removed which show leakage through the tell-tale hole.

The Interstate Commerce rules further require that the inner ends of the tell-tale holes must be kept closed with a fire-proof porous material that will exclude foreign matter and permit leakage of steam or water, if the bolt is broken or fractured, into the tell-tale hole, and that when this test is completed the ends of the tell-tale holes must be closed with material of different color from that removed and a record kept of colors used.

In order to avoid the troublesome, tedious and time-consuming work of removing the caps of the large number of staybolts on a locomotive and the necessity of stripping the entire fire-box of the jacket, lagging, piping, etc., and the withdrawal of the locomotive from service several days each time the caps must be removed and the staybolts inspected, it has been a common practice to use a special type of flexible staybolt with a copperized tell-tale hole complying with the re-

quirement above-noted, that is, a tell-tale hole of "blind" character extending from its inner end to a point in its head portion near its opposite or outer end, from which point outward the hole is "blind" or closed. 55 These staybolts are difficult to make on account of drilling the small hole into the head and treatment of the tell-tale hole, and there is no assurance that the hole is drilled accurately in the center, so that faulty bolts 60 are liable to be produced and put into use. Ordinarily this type of bolt employs a solid or screwed on spherical head fitted to turn in a casing consisting of a sleeve and cap, the cap being especially designed to close 65 the casing against any leakage which may occur between the head and its seat due to expansion, contraction or wear of these parts or imperfections causing imperfect seating.

One objection to such construction of 70 flexible tell-tale staybolts is that in riveting down the inner end of the bolt the tell-tale hole is liable to be closed. In such event the hole must be reamed out, cleaned by means of an air cleaner for removal of chips 75 and other foreign particles, and all such tell-tale holes tested by means of an electrical testing tool such as before referred to which indicates by electric contact and the operation of a signal when the hole is entirely 80 clear and clean.

Another objection to such construction of 85 flexible tell-tale staybolts is that in case of leakage at the outer end of the bolt it is impossible to tell whether such leakage is due solely to a faulty seat or to a break in the bolt, or both, and therefore it is difficult to tell what work is necessary to remedy the difficulty.

Still another objection to such flexible tell-tale bolts is that between inspections fracture of a staybolt may occur which will not be indicated in the manner relied upon by leakage of water and steam through the porous closure, and the tell-tale holes of such 95 bolts may become clogged with boiler scale so that no indication of the break can be given in the designed way. When this occurs it is necessary to clean out the tell-tale holes of all clogged bolts and to electrically 100

test the same by means of an electrical test seat of the head being formed by the wall tool as previously described to indicate by electric contact and the operation of a signal when the hole has been thoroughly cleaned. After all bolts have been thus tested to determine whether or not their tell-tale holes are cleaned, all bolts not showing clean bolt holes must be removed. All bolts which have successfully undergone the clean tell-tale hole test must then be tested for breaks or fractures by applying water pressure to the boiler, the tell-tale holes closed by porous plugs of different color from those previously used, and elaborate records of all such tests kept; and all bolts indicating by leakage, breaks or fractures into the tell-tale holes, must be removed.

As a result of the several objections above-mentioned flexible tell-tale staybolts of the type in general use are comparatively expensive to install and to maintain in serviceable condition, and the difficult and tedious inspection work required encourages faulty inspection work and necessitates the withdrawal of the locomotive from service for a considerable period each time general inspection and repairs are made.

The object of our invention is to provide a staybolt so constructed as to allow of the use of a tell-tale hole of "peep-sight" type, or one extending continuously therethrough, so that breaks or fractures will be at once indicated by leakage of steam or water at one end or the other end of the bolt; so that the condition of the tell-tale hole may at all times be determined by visual inspection, i. e., by daylight or other light test and looking through the tell-tale hole or with a rod; and so that cleaning of the tell-tale hole may be performed in an easy and rapid manner and without the use of complex tools.

A further object of the invention is to provide a construction of bolt head and casing and joint-closing means effecting a sealing connection therebetween, whereby an open instead of a closed type of casing may be employed to permit escape of steam or water for break or fracture indication at the outer end of the bolt, as well as at the inner end thereof, while at the same time normally maintaining a tight steam and water tight joint between the head and casing.

In another application, filed of even date herewith, Serial No. 509,996, we have shown the principles of our invention applied to a staybolt having a sleeve and cap form of casing in which the sleeve is fitted in an opening in an outer boiler sheet and is provided with inner and outer seats for the head.

In the present application we have shown the principles of our invention applied with the same objects in view to a casing arranged and welded on the outer side of the outer boiler sheet and in which casing an outer seat for the head is formed, the inner

of the bolt opening in such boiler sheet.

In the drawings:

Fig. 1 is a longitudinal section through one form of staybolt embodying our invention applied to boiler sheets. 70

Fig. 2 is a fragmentary view looking toward the outer side of the outer boiler sheet.

Fig. 3 is a bottom plan view of the closure member or cap of the casing shown in Fig. 1. 75

Fig. 4 is a bottom plan view of the bushing.

Fig. 5 is a side elevation, partly in section, of the same.

Fig. 6 is a bottom plan view of the soft metal washer.

Fig. 7 is a side elevation, partly in section, of the same.

Fig. 8 is a sectional view, similar to Fig. 1, of the outer end of another form of staybolt structure embodying our invention. 85

Fig. 9 is a section on the line 9—9 of Fig. 8.

Fig. 10 is a sectional view, similar to Fig. 1, of the outer end of still another form of staybolt structure embodying our invention. 90

Fig. 11 is a section on line 11—11 of Fig. 10.

Fig. 12 is a view showing a separately formed inner bolt head member applied to 95 the bolt shank.

Fig. 13 is a similar view of the outer end of a bolt proper, showing the use of a separately formed end extension applied thereto. 100

Referring now more particularly to the drawings, and especially to Figs. 1 to 7, inclusive, 1 and 2 respectively designate the inner and outer sheets of a fire-box or other portion of a boiler. In the sheet 1 is a threaded opening 3 in which is fitted and through which extends the inner threaded end 4 of the bolt 5, a projecting portion of which end 4, after the bolt is applied, is upset or hammered down to form the head 6. 105

The opposite or outer end of the bolt is provided with a hemispherical head or inner head member 7, which is arranged at the point of intersection of the main portion of the body or shank of the bolt and a reduced stem or extension 8. This end extension 8 is preferably of reduced diameter with respect to the bolt body and may be externally of any suitable form. The head or head member 7 is given a cup-shaped formation by the provision of an annular socket or recess 9 between the same and the extension 8, for a purpose hereinafter described. 115

The outer end of the shank of the bolt and its end and coacting parts are disposed within a casing arranged on the outer side of the sheet 2 and comprising an annular body member 10 and a cap or closure member 11 having a threaded or other suitable engagement therewith. These members are suit- 125

- ably constructed to provide opposing faces between which may be fitted a metallic gasket 12, adapted to prevent leakage of water or steam through the joint therebetween.
- 5 The member 10 of the casing is welded to the sheet 2, as indicated at 13, and receives the outer end of the head member 7 which has its convex seat face 14 arranged for pivotal seating engagement with a concaved 10 seat face 15 on the sheet 2 intersecting the outer portion of the opening 16 in the sheet through which the bolt body extends, whereby inner pivotal and joint-closing surfaces are provided between the bolt and the boiler 15 sheet.
- The closure or cap member 11 of the casing is formed in its underside with a substantially hemispherical socket having an outer joint-closing seat face 17 and an opening 18 20 in its outer wall intersecting said seat face. The outer end of the stem 8 projects through and is exposed by the opening 18, and slidably mounted on said stem for adjustment relative to the head member 7 and seat 17 is 25 a bushing or outer head or joint-closing member 19 the convex seat face 20 of which pivotally engages the seat surface 17 and closes the joint between the bolt end and said seat surface. The seat surfaces 15 and 30 17 and the head surfaces 14 and 20 are inscribed on arcs having the same center of motion, so that the parts 7 and 19 constitute complementary inner and outer members of a bolt head pivotally movable to allow of the 35 intended flexing movements of the bolt and respectively closing the joints between the bolt and sheet 2 and between the bolt and the opening 18 in the cap 11 through which the bolt extremity 8 is exposed.
- 40 The bushing or outer head member 19 is provided in its underside with a cavity 21 receiving a conical gasket 22 of lead or other soft metal, whereby the joints between said parts and the stem or extension 8 are closed.
- 45 This gasket 22 rests upon a washer 23 which is resiliently supported by a coiled spring 24 seated in the groove 9 and surrounding the stem 8 between said washer and the bottom of the groove, the pressure of which 50 spring, regulated by the adjustment of the cap 11, holds the gasket tightly seated against the bushing and the latter against the outer seat face 17, thus providing an automatic adjustment to compensate for expansion, contraction and wear and to keep 55 the joints constantly tight.
- The bolt is provided with a tell-tale hole 25 extending longitudinally through it, from end to end, including the extension 8. This 60 hole, therefore, unlike a blind tell-tale hole terminating at one end in the head of the bolt, may be easily and accurately formed and furnishes a passage opening through both ends of the bolt. Such a hole, if temporarily closed at its inner end in the forma- 65
- tion of the head 6, may be easily and conveniently cleaned or reamed out and cleared of all particles without the necessity of employing a pneumatic cleaning tool or an electric testing device, since any sort of a cleaning instrument may be employed and whether the hole is clogged or not may be determined instantly by daylight or artificial light visual observation, that is, by simply looking through the bolt hole. The inner 70 end of the hole is closed in service in the prescribed manner by employing a porous plug 26 through which, in the event of breakage of the bolt or fracture into the hole, steam or water may discharge at such end 75 of the bolt to indicate the break, while the plug serves normally to prevent any of the products of combustion from the fire-box entering and clogging the hole. If conditions are favorable, however, the porous plug 80 may be omitted. In the event of leakage between the bolt head and its seats, which is not liable to occur because of the self-adjusting action of the joint-closing elements, the nature or character of this leakage 85 may be readily determined and distinguished from a break or fracture leak. Also in case of fracture or leakage, escape of water will occur from either or both ends, and at least one of the ends, of the bolt 90 95 100 105 110 115 120 125 130

improved construction of staybolt combines all the advantages of the rigid hollow stay-bolt with tell-tale hole with the advantages of the flexible type, while overcoming the stated and other well known disadvantages of the original rigid and conventional types of flexible staybolts. The present invention also provides a type of flexible staybolt in which the casing for the bolt head may be arranged entirely on the outer side of the outside boiler sheet, and a sealing connection provided between the head and the boiler sheet and casing, in such manner that the outer end of the bolt may be exposed for steam and water escape while a normally leak-proof connection between the bolt and casing is maintained.

The construction of the staybolt may be modified in many and various ways within the spirit and scope of our invention. One such modification is shown in Figs. 8 and 9, in which the bolt 5^a has its head member 7 provided in its rim portion with notches 7^a whereby a type of wrench or other tool may be engaged therewith for securing the end 4 of the bolt in the hole 3 of sheet 1, so that this work may be done from the outside. This modified construction of bolt also employs a cup-shaped unitary type of casing 10^a welded to the sheet 2, and which may be used when this form of casing is desired. Other features of construction such as shown in our aforesaid copending application may also be used in this type of bolt.

Another form of our invention is shown in Figs. 10 and 11, in which the groove 9 is omitted and there is substituted for the coil spring 24 a concavo-convex plate spring 24^a which functions the same as the spring 24.

Still other forms of our invention are shown in Figs. 12 and 13. In Fig. 12 the inner bolt head member 7^a is threaded, and also welded or otherwise fixed, to the bolt shank, if desired, while in Fig. 13 a construction is shown in which the bolt extension 8^a is formed separately from and threaded and welded at its inner end to the bolt shank. The structure shown in Fig. 12 may be used with either a coil spring or plate spring and adapts the bolt to be applied from the fire-box side while the separate extension 8^a of Fig. 13 permits of the application of such extension to conventional staybolts in stock with slight modification.

It will be understood that the gaskets and washers employed may be of metals of suitable degrees of hardness or softness; and that by making the bushing or outer head member wholly of bearing metal the washers may be dispensed with.

While the structures disclosed, for exemplification, are preferred, it will, of course, be understood that many changes in the form, proportion, construction, and arrange-

ment of parts, other than those disclosed, may be made within the scope of the claims without departing from the spirit or sacrificing any of the advantages of the invention, and that the principles of the invention may be applied to all conventional forms of staybolts of the general type disclosed now in use.

Having thus fully described our invention, we claim:—

1. In a pivot head structure for staybolts, and in combination with a bolt head casing having inner and outer walls provided with aligned openings and partly spherical seats about said openings, a bolt body provided with a tell-tale opening extending therethrough from end to end thereof and having an end portion projecting through the said openings in the walls of the casing, said end portion of the bolt embodying a substantially hemispherical inner head member presenting a convex pivot face engaging the seat in the inner casing wall and a straight transverse outer face, an extension of reduced diameter with respect to the bolt body projecting beyond the transverse face outward through the opening in the outer casing wall, an apertured outer head member slidably engaging said bolt end extension and having a convex outer pivot face engaging the seat in the outer casing wall and a concaved inner face, the convex faces of said head members being arranged on arcs of one and the same circle so that said head members cooperate to form a pivot head of spherical outline for universal pivotal motion of the bolt on said seats, a packing member slidably engaging the bolt end extension and having an outer convex face engaging the concaved face of the outer head member, a washer about the bolt end extension and backing the packing member, and a spring disposed between the inner bolt head member and the packing member and operating to yieldingly press the outer bolt head member and packing member outwardly.

2. In a pivot head structure for staybolts, and in combination with a bolt head casing having inner and outer walls provided with aligned openings and partly spherical seats about said openings, a bolt body provided with a tell-tale opening extending therethrough from end to end thereof and having an end portion projecting through the said openings in the walls of the casing, said end portion of the bolt embodying a substantially hemispherical inner head member presenting a convex pivot face engaging the seat in the inner casing wall and a straight transverse outer face, the latter having an annular groove therein, an extension of reduced diameter with respect to the bolt body projecting beyond the transverse face outward through the opening in the outer casing wall,

an apertured outer head member slidably engaging said bolt end extension and having a convex outer pivot face engaging the seat in the outer casing wall and a concaved inner face, the convex faces of said head members being arranged on arcs of one and the same circle so that said head members cooperate to form a pivot head of spherical outline for universal pivotal motion of the bolt
5 on said seats, a packing member slidably engaging the bolt end extension and having an outer convex face engaging the concaved face of the outer head member, a washer about the bolt end extension and backing the packing member, and a coiled spring seated in the groove in the transverse face of the inner bolt head member and disposed between the inner bolt head member and the packing member and operating to yieldingly
10 press the outer bolt head member and packing member outwardly.
